UNITED STATES PATENT OFFICE.

EDWIN H. GILBERT, OF WILKINSBURG, PENNSYLVANIA, ASSIGNOR TO WESTINGHOUSE ELECTRIC & MANUFACTURING COMPANY, A CORPORATION OF PENNSYLVANIA.

INCLOSED FUSE.

1,246,417.

Specification of Letters Patent. Patented Nov. 13, 1917.

Application filed May 1, 1913. Serial No. 764,804.

To all whom it may concern:

Be it known that I, EDWIN H. GILBERT, a citizen of the United States, and a resident of Wilkinsburg, in the county of Allegheny and State of Pennsylvania, have invented a new and useful Improvement in Inclosed Fuses, of which the following is a specification.

My invention relates to protective devices for electrical circuits and it has special reference to inclosed fuses of the renewable type.

The object of my invention is to provide a reliable and inexpensive inclosed fuse which shall be adapted to convenient renewal and shall embody means for visibly and plainly disclosing the condition thereof.

Heretofore, many inclosed fuses have been more or less troublesome to renew by reason of the filling material or incombustible powder which was allowed to remain loosely in the casing. The indication of the condition of the fuse was also not so plain as might be desired. Moreover, it was possible to substitute a fuse of different rating from that specified as proper for the particular circuit.

According to my invention, I provide an incasing member and a renewable element adapted for insertion therein and comprising a cartridge containing both the fuse and the powder, thereby making the renewal of a burned-out fuse very convenient and rapid. In addition, the cartridge has one portion reduced in size and a paper band is partially attached thereto. Upon rupture of the fuse, the reduced portion expands and bursts the paper, thereby plainly disclosing the condition of the fuse. Inspection of the paper band, upon which are printed the voltage and current ratings of the inclosed fuse, is permitted by means of a small window of glass or other suitable material disposed in the outer casing opposite the printed ratings. It will be understood that the rating figures cannot be altered without destroying the paper band. Moreover, substitution of a fuse having a capacity larger than that specified as proper for the particular service conditions may be immediately detected upon inspection.

In the accompanying drawings, Figure 1 is a view, mainly in longitudinal section but partially in elevation, of a complete protec-

tive device embodying my invention; Fig. 2 is a sectional view, on the line II—II of Fig. 1; Fig. 3 is a view in longitudinal elevation taken at right angles to the view of Fig. 1; Fig. 4 is a sectional view, on the line IV—IV of Fig. 3; Fig. 5 is a view in longitudinal elevation of a complete protective device embodying my invention and employing a modified form of the accessories thereto; Fig. 6 is a partial view in longitudinal section taken at right angles to the view of Fig. 5; and Fig. 7 is a sectional view, on the line VII—VII of Fig. 6, all sectional views being taken as looking in the direction of the corresponding arrows.

Referring to the drawing, a protective device 1 for electric circuits comprises an outer casing 2 with removable end ferrules 3, and an inner cartridge 4 containing a fusible link 5.

The outer casing 2 is preferably cylindrical in shape and made of some strong and non-conducting material such as fiber. A side opening 6, that is disposed intermediate the ends, is provided with a window 7 of glass or other suitable transparent material, for a purpose hereinafter specified. The end ferrules 3 are made of spun brass or a suitable equivalent and are adapted to engage suitable clips in a fuse block (not shown). Each ferrule is provided with a plurality of side openings 8 to receive screws 9 and 10. A disk 11, substantially U-shape in form, and having a plurality of arms 12, is transversely disposed within the outer end 90 of each ferrule 3 and is provided with an integral stationary jaw 13, and a movable jaw 14 which are adapted to grip the projecting end of the fuse link 5, when acted upon by the screw 9. The jaw 14 is adapted for translative movement by means of a transversely disposed pin 15 rigidly associated with said jaw and working in a plurality of oppositely disposed slots 16 in the arm 12 of the disk 11. A ring 17 is disposed within each end of the casing 2 and is provided with a plurality of openings that are threaded to engage the screws 9 and 10. The ring 17 is thereby forced outwardly against the casing and tends to tighten the engagement of the casing and the ferrule 3.

The inner cartridge 4 comprises an en-

velop 18, the inclosed fusible-link 5, a body of incombustible powder 19, and a label 20 disposed around said envelop. The link 5 and powder 19 are old and well known in the art and need not be further described. The envelop 18 preferably consists of a closed cylinder of fiber or similar material having one portion 21 crimped to reduce the diameter, and the label 20 is disposed around said crimped portion. The label is provided with a plurality of spaced perforated lines 22, and it is glued to the envelop 18 between these lines only, although closely fitting said crimped portion elsewhere. The voltage and current ratings of the fuse, as hereinbefore indicated, are printed on the label 20 near the perforated lines 22, and are disposed opposite the window 7 in the casing 2, as indicated at 23. The ends of the fusible link 5 severally extend beyond the ends of the envelop 18 and are adapted to be held by the jaws of the ferrules 3, as hereinbefore described.

In Figs. 5, 6 and 7, the body of the fuse is the same as that just described, but the end ferrules 24 are provided with knife-blade contact members 26 for engagement with switch jaws on a fuse block (not shown). Each ferrule 24 is provided with a slot 25 through which the knife-blade contact member 26 projects. Integral with the member 26, and offset a little to properly engage the fusible link 5, is a stationary jaw 27. A disk 28, disposed transversely within the outer end of the ferrule 24 serves as an additional support for the combined contact member 26 and stationary jaw 27, and is provided with a countersunk slot 29 for a purpose to be described. A movable jaw 30 is disposed to coöperate with said stationary jaw 27 for gripping the exposed end of the fusible link 5. A pin 31 is rigidly associated with said movable jaw to work within the countersunk slot 29 when acted upon by the screw 9. The expansion ring 17 and the screw 10 are used in the same capacities as before.

Assuming the protective device to be connected in an electrical circuit and that a dangerous overload current suddenly flows through the line, the operation of the device is as follows: The fusible link 5 ruptures, presumably near its middle and narrowest section, thereby opening the circuit. The explosive action causes the reduced portion 21 of the envelop 18 to expand, thereby breaking the label 20 on one or both of the perforated lines 22 and clearly indicating that the fuse has blown.

To put the protective device in operative condition again, one end ferrule is removed, the old cartridge taken out and a new one slipped in, the ends of the fusible link being clamped within the jaws associated with the end ferrules.

It will be understood that modifications of the protective device hereinbefore described may be made within the spirit and scope of my invention, and I desire that only such limitations shall be imposed as are indicated in the appended claims.

I claim as my invention:

1. A protective device for electric circuits embodying an incasing member having a window therein, a yieldable renewable member having a portion of reduced cross-section adapted for insertion therein and comprising a fusible body and associated incombustible material, and means disposed around the portion of reduced cross-section that is adapted to burst upon the rupture of the fusible body. 75

2. A fuse device comprising a yieldable fuse-carrying member, and a band of paper disposed around a portion of the yieldable fuse-carrying member adapted to burst upon the expansion of the said fuse-carrying member when the fuse is ruptured. 85

3. A fuse device comprising a yieldable fuse-carrying member having its central portion reduced in size, a band of paper so disposed with respect to the reduced portion of the fuse-carrying member that it ruptures when the fuse blows. 90

4. A protective device for electric circuits embodying a yieldable fuse-carrying member having one portion reduced in size, a signal band disposed around the said reduced portion to be set by the expansion of said reduced portion when the fuse is ruptured, and means for connecting said fuse in said circuit. 95

5. A protective device for an electric circuit comprising a yieldable fuse-carrying member having one portion reduced in size, a band of fragile material attached to said reduced portion and adapted to burst upon the expansion of the said reduced portion when the fuse is ruptured. 105

6. A protective device for electric circuits embodying a yieldable fuse-carrying member having one portion reduced in size, a band of fragile material attached to said reduced portion which bursts upon expansion of said portion by reason of the rupture of said fuse, and means for connecting said fuse in said circuit. 110

7. A protective device for electric circuits embodying a yieldable cartridge carrying a fuse and having one portion reduced in size, a band of paper partially attached to said reduced portion which bursts upon expansion of said portion by reason of the rupture of said fuse, and means for connecting said fuse in said circuit. 115

8. A protective device for electric circuits, comprising a closed yieldable removable cartridge carrying a fuse, and a band of fragile material partially attached to a central portion of the removable cartridge 120

and adapted to burst when the cartridge yields upon the rupture of the fuse.

9. In a protective device for electric circuits, the combination with an outer protective casing having a window therein, of an inner yieldable renewable cartridge carrying an inclosed fuse and having one portion reduced in size, a band of fragile material partially attached to said reduced portion for disclosing through the window the condition of the fuse, and means for connecting said fuse in said circuit.

10. In a renewable fuse, the combination with a cartridge member having a window therein, of a renewable yieldable fuse-carrying member inserted therein and having one portion reduced in size, and a visible signal disposed around the said reduced portion to

indicate by bursting when the fuse is ruptured.

11. In a renewable fuse, the combination with a cartridge member having a window therein, of a renewable yieldable fuse-carrying member inserted therein and having one relatively short portion of reduced diameter, and a band of fragile material attached to said reduced portion that will burst upon expansion of the said reduced portion by reason of the rupture of said fuse.

In testimony whereof, I have hereunto subscribed my name this 26th day of April, 1913.

EDWIN H. GILBERT.
